PIVOT

Willis H. Gille, St. Paul, Minn., assignor to Minneapolis-Honeywell Regulator Company, Minneapolis, Minn., a corporation of Delaware

Application December 31, 1949, Serial No. 136,383

2 Claims. (Cl. 308—2)

1

This invention relates to low-friction pivots, particularly of the knife edge type.

The object of the invention is to provide a knife edge pivot structure that may be made on a mass production basis without the necessity for accurate machining of the parts. The interacting parts of the pivot may be sheet metal stampings assembled without further processing as they come from the punch press.

In the illustrated form of the invention the two cooperating parts of the pivot are flat sheet metal parts, the edges of which form right angle knife edges. The knife edges of each part engage flat surfaces of the other part, the arrangement being such that the engaging portions of the two parts lie in a straight line. By having the two parts cross at other than ninety degrees a composite knife edge pivot is provided that permits a limited amount of pivotal movement between the parts.

Figure 1 of the drawing is an elevation of a snap switch incorporating the novel pivot structure.

Figure 2 is a fragmentary plan view taken substantially on line 2—2 of Figure 1, and

Fig. 3 is a fragmentary elevation as seen from the right of Figure 1.

Other novel features of the illustrated device are covered in the application of Murrell F. Kautz, Serial No. 136,351, filed on December 31, 1949, now Patent No. 2,582,834.

The illustrated snap switch has a base 10 carrying a pair of terminals 11 and 12. The terminal 11 is connected to a bracket 14 that carries a stationary contact 15. Terminal 12 is connected to a bracket 17 that pivotally carries a switch arm 18 in a manner to be described hereinafter. The switch arm 18 comprises an armature 20 that cooperates with a magnet 21 to produce snap action of the switch arm. An overarm 22 is secured to the right-hand end of armature 20, the relative positions of the armature 20 and overarm 22 being adjustable by means of a screw 23 as described in the above mentioned Kautz application. The overarm 22 carries a spring blade 24 that carries a movable contact 25 adapted to cooperate with the stationary contact 15. The movable contact 25 and the spring blade 24 are electrically connected to the bracket 17 by pigtail 26.

A bracket 29 secured to the left-hand end of the base 10 carries an actuating arm 30 in a manner to permit some pivotal movement of the arm 30. A push button 31 engages a spring blade 32 that is secured to the left-hand end of the arm 30, the blade 32 providing a resilient connection

2

between the push button 31 and the arm 30. The blade 32 serves to store energy as the push button 31 is depressed, the energy being available to produce snap action as the armature 20 moves away from the magnet 21. A link 34 interconnects the right-hand end of the arm 30 with the right-hand end of the armature 20 to transmit force therebetween.

The bracket 17 is provided with a pair of spaced upstanding extensions 17a that form an angle with respect to the base of slightly less than 45°. Each of the extensions 17a is provided with a shoulder 17b, the upper edges of the shoulders 17b being in alignment. Since the bracket 17 is a sheet metal stamping it is convenient to form the shoulder 17b in the same stamping operation that forms the bracket 17 as a whole into its developed shape. The armature 20 is provided with a pair of extensions 20a that form an angle of slightly less than 45° with the remainder of the armature. Each of the extensions 20a is provided with a shoulder 20b, the lower edges of which are in alignment. Since the shoulder 20b is formed in the same stamping operation that forms the remainder of the armature 20 in its developed state, the shoulder 20b forms a right angle with the lower surface of the extension 20a.

When the switch arm 18 is placed on the bracket 17 with the extension 20a of the armature engaging the extension 17a of the bracket, the shoulder 17b will engage the under surface of the extension 20a and the shoulder 20b will engage the upper surface of the extension 17a. The upper surfaces of the two extensions 17a are disposed in the same plane. Likewise the lower surfaces of the extensions 20a are disposed in the same plane. Since the cooperating engaging edges of the shoulders 17b and 20b are in alignment, a pivotal axis is established as indicated by the line A—A in Figures 2 and 3.

Pivots embodying the same principle are also employed in the pivotal connection between the link 34 and the switch arm 18 and between the link 34 and the arm 30. These pivotal connections also involve sheet metal stampings that cross at an angle other than 90 degrees. The upper end of the link 34 is provided with a pair of shoulders 34a that engages the under surface of an upwardly bent portion 30a of the arm 30. The portion 30a is provided with a rectangular slot 30b, the lower outer edge of which provides a knife edge engaging the flat portion of the link 34 intermediate the shoulders 34a. The lower end 55 of the link 34 has shoulders 34c having edges

that engage the flat upper surface of an angularly disposed extension 20c of the armature 20. The extension 20c of the armature has a rectangular slot 20d, the outer and upper edge of which provides a knife edge that engages link 34 intermediate the shoulders 34c. It will be seen that in each of these latter described pivotal connections three knife edge pivots mutually cooperate to form a pivotal connection between the parts. Since the knife edges are in alignment a low friction knife edge is provided.

When the push button 31 is depressed to bias the arm 30 downwardly with sufficient force to overcome the magnetic attraction of the magnet 21 the armature 20 and switch arm 18 will pivot suddenly in a clockwise direction about the axis A to a point in which the left-hand end of over-arm 22 engages an inwardly bent portion 29a of the bracket 29. Some pivotal movement will, of course, occur between the link 34 and the arm 30 and also between the link 34 and the switch arm 18. Movement will be in a reverse sense when the force on the push button 31 is sufficiently reduced.

While the novel pivot structure has been described in connection with a snap switch it will be evident that it would find application in many other structures where relatively friction-free pivotal movement is desired. The scope of the invention is to be determined only by the appended claims.

I claim as my invention:

1. A pivot structure comprising a support, a pair of arms extending outwardly from said support, each of said arms having a flat surface lying in the same plane and each of said arms being notched to form a shoulder the edges of said shoulders lying in a straight line in said

plane, a member extending between said arms and having laterally extending portions engaging said arms, said portions having flat surfaces lying in a common plane and engaging the edges of said shoulders, and said portions further having shoulders with edges lying in a straight line within the plane of the flat surfaces of said portions, said edges engaging the flat surfaces of said arms.

10 2. A pivot structure comprising a support, a pair of arms extending outwardly from said support, each of said arms having a flat surface lying in the same plane and each of said arms being notched to form a shoulder the edges of said shoulders lying in a straight line in said plane, a member extending between said arms and having laterally extending portions engaging said arms, said portions having flat surfaces lying in a common plane and engaging the edges of said shoulders, and said portions further having shoulders with edges lying in a straight line within the plane of the flat surfaces of said portions, said edges engaging the flat surfaces of said arms, and means limiting pivotal movement of said member to a range in which the foregoing relation of the parts is maintained.

WILLIS H. GILLE.
